Design U.S. Appl. No. 29/690,322, filed May 7, 2019 entitled "Stove".

(Continued)

Primary Examiner — Ricky Pham(74) *Attorney, Agent, or Firm* — Middleton Reutlinger(57) **CLAIM**

The ornamental design for a stove, as shown and described.

DESCRIPTION

FIG. 1 is an upper perspective view of a stove design; FIG. 2 is a second upper perspective view of the stove design of FIG. 1;

FIG. 3 is a front view of the stove design of FIG. 1;

FIG. 4 is a top view of the stove design of FIG. 1;

FIG. 5 is a first side view of the stove design of FIG. 1; and,

FIG. 6 is a second side view of the stove design of FIG. 1.

The broken line disclosure represents unclaimed portions or unclaimed boundaries of the stove in which the design is embodied.

1 Claim, 6 Drawing Sheets(56)
